GARMENT-STAY.

1,106,481.

Specification of Letters Patent. Patented Aug. 11, 1914.

Application filed July 17, 1912. Serial No. 710,007.

To all whom it may concern:

Be it known that I, FRANK L. O. WADSWORTH, a resident of Sewickley, in the county of Allegheny and State of Pennsylvania, have invented a new and useful Improvement in Garment-Stays, of which the following is a specification.

This invention relates to the construction of stays or stiffeners for corsets and other 10 garments or wearing apparel.

The object of the invention is to provide a stay possessing greater stiffness and resiliency for a given weight of wire than stays as heretofore constructed.

15 Generally stated, the invention consists in constructing the stay in the form of a flat wire spring composed of a plural wire strand or strands, such plural wire strand or strands being formed into a series of loops, eyes or convolutions and portions of said strand or strands being twisted.

20 In the accompanying drawings, Figures 1, 2 and 3 illustrate different forms of stays embodying the invention; Fig. 4 is a transverse section on the line 4—4, Fig. 1; and Fig. 5 is a section on the line 5—5, Fig. 1.

25 In the fabrication of the stay instead of using a single wire as a strand, as heretofore, I make use of a strand or strands composed of a plural number of wires, the drawings showing a strand 1 composed of three wires *a*, *b* and *c*, although any desired number of wires may be used for the strand. For a given size and strength of stay, each 30 of the several wires composing a plural wire strand will, of course, be lighter and of less cross sectional size than when a single wire is employed for the strand as heretofore. The stay can be formed of either one or any 35 desired number of such plural wire strands. Fig. 1 shows a single plural wire strand 1 bent alternately back and forth to form two series of oppositely disposed loops or eyes 2 with transverse portions or crossings 3

40 substantially normal to the longitudinal axis of the stay. Fig. 2 shows a stay also formed from a single plural wire strand bent alternately back and forth to form the two series of oppositely disposed loops or eyes, but 45 which in this case are of bulbous or general pear shape so that the edges of adjacent loops or eyes overlap, as at 4, the crossings 3 in this case being reversely bent or of general S-shape. Fig. 3 shows a stay com-

posed of two plural wire strands 1 and 1^a, 55 each bent alternately in opposite directions to form two series of oppositely disposed eyes 2, and in which the two wires are interlaced in such manner that the loops or eyes in one strand bridge the spaces between the 60 loops or eyes in the other strand, adjacent loops or eyes in the stay structure overlapping, as shown. Many other forms of stays can be constructed from one or more plural wire strands, and the invention is not limited as to the number of such plural wire strands used in the fabrication of the stay. 65

The stays illustrated are flat wire springs. They preferably will be slightly concave, that is, the transverse portions or crossings 70 3 are slightly deflected out of the flat plane of the stay, toward one side, as shown in Fig. 4, so that the stay as a whole has a slight transverse curvature. The effect of this is to render the stay stiffer and also 75 cause it to fit more neatly to the contour of the body.

The wires constituting a strand may be twisted together in any suitable way. Preferably, however, the strand as a whole 80 will be twisted in those portions forming the crossings 3, and twisted in such direction that the twist in all of the crossings, viewing the stay as a whole, runs in the same direction. The effect of this is to render the 85 stay stiffer against stresses tending to flex it in one flatwise direction as compared with the other. The twist in these crossings can be placed therein in any manner and can be readily effected in the fabrication of the 90 stay in various ways, one manner being according to my application Serial No. 728,277, filed October 28, 1912. The twists are carried beyond the elastic limit of the metal so that the several crossings of the 95 completed stay are under an initial twist or torsional set.

It is well known that if a wire or rod has been twisted in one direction beyond the elastic limit of the metal, it resists stresses 100 tending to twist it in the same direction to a greater degree than it resists stresses tending to twist it in the opposite direction. Therefore, by imparting to the several crossings an initial twist or torsional set beyond 105 the elastic limit of the metal, it is obvious that a flexure of the stay in the direction tending to twist the several crossings in the

same direction in which they are already twisted, will meet with materially greater resistance than a flexure of the stay in the opposite direction. Consequently, the stay is stiffer in one flatwise direction than in the other. The permanent set or twist imparted to the wire strands also increases the elasticity or resiliency of the metal and thereby enables the stay to resist taking a permanent set much better than when the wire has no such initial twist or torsional set. The twisting of the wires to impart the permanent set thereto also has the effect of tying or binding together the wires forming each strand, so that there is no liability of the wires of a strand becoming displaced or separated from each other.

The twists in the several crossings run in such direction as to give the increased stiffness and resiliency when the stay is flexed with its concave side on the outside of the curve, so that the concavity reinforces or assists the torsional set or twist. The stays are so placed in the garment that the concave side thereof is inward or toward the body of the wearer. Consequently, the stays most effectively take care of the stresses to which garment stays are subjected in actual use. This enables the stay to be either formed of lighter wire than similar stays as heretofore constructed, or if formed of wire of the same size or weight, will produce a stay which is much stronger, stiffer and more resilient than if constructed as heretofore.

Another advantage of a plural wire strand stay is due to the fact that the wires themselves being of smaller cross section than if the stay were constructed of a single wire strand, such wires will not take a permanent set or bend as readily as the single larger wire, that is, the strand can be bent to a much sharper angle without taking a permanent set than if it were formed of a single wire of the necessary strength and stiffness. Still another advantage is that the stay can be much more readily fabricated by reason of the greater ease with which small sized wires can be bent and manipulated.

50 What I claim is:—

1. A garment stay comprising a flat wire spring composed of a plural wire strand or strands formed into a series of loops, portions of said strand or strands being under

an initial twist or torsional set running in the same direction in corresponding parts of the stay.

2. A garment stay comprising a flat wire spring composed of a plural wire strand or strands formed into a series of loops, portions of said strand or strands being under an initial twist or torsional set running in the same direction in corresponding parts of the stay, said stay being of slightly concaved form in cross section.

3. A garment stay comprising a flat wire spring composed of a plural wire strand formed into oppositely disposed loops with transverse connecting portions or crossings extending from edge to edge of the stay, said transverse portions or crossings being under an initial twist or torsional set, the twist in all said crossings running in the same direction.

4. A garment stay comprising a flat wire spring composed of a plural wire strand formed into oppositely disposed loops with transverse connecting portions or crossings extending from edge to edge of the stay, said transverse portions or crossings being under an initial twist or torsional set, the twist in all said crossings running in the same direction, said transverse portions or crossings being deflected sidewise out of the plane of the stay.

5. A garment stay comprising a flat wire spring composed of a plural wire strand or strands bent to form a series of oppositely disposed loops with the sides of contiguous loops overlapping, the transverse portions or crossings being initially twisted, the twist in all said crossings running in the same direction.

6. A garment stay comprising a flat wire spring composed of a plural wire strand or strands bent to form a series of oppositely disposed loops joined by transverse portions or crossings, said crossings being deflected toward one side out of the plane of the stay, and being initially twisted, the twist in all said crossings running in the same direction.

In testimony whereof, I have hereunto set my hand.

FRANK L. O. WADSWORTH.
